C. R. HULTGREN

PACKAGING DEVICE AND METHOD

Filed Nov. 3, 1923

UNITED STATES PATENT OFFICE.

CHARLES R. HULTGREN, OF CHICAGO, ILLINOIS, ASSIGNOR TO S. KARPEN & BROS., OF CHICAGO, ILLINOIS, A CORPORATION OF WEST VIRGINIA.

PACKAGING DEVICE AND METHOD.

Application filed November 8, 1923. Serial No. 672,681.

To all whom it may concern:

Be it known that I, CHARLES R. HULTGREN, a citizen of the United States, residing at Chicago, in the county of Cook and 5 State of Illinois, have invented new and useful Improvements in Packaging Devices and Methods, of which the following is a specification.

This invention relates particularly to an 10 improved device and method for binding packages, bundles, boxes or the like.

The primary object is to provide a simple device and an economical method for binding boxes, bundles, etc.

15 The invention is illustrated in its preferred embodiment in the accompanying drawing, in which—

Fig. 1 represents a perspective view of a box or bundle secured by means of the improved packaging device, the view illustrating the manner in which the metal binding tape is drawn taut; Fig. 2, a broken front elevational view of the implement employed in performing the binding operation; Fig. 2^a, a broken vertical sectional view illustrating the manner in which the metal tape is gripped by the implement during the stretching or tightening operation; Fig. 3, a broken perspective view of the improved 20 binding or securing device; Fig. 4, a broken perspective view illustrating the condition of the binding device while it is being drawn taut; Fig. 5, a similar view of the device after the clip has been deformed to secure 25 the binding tape; and Fig. 6, an enlarged broken sectional view of the binding device in its final condition.

In the illustration given, A represents a package, box or bundle; B, B, the improved 30 binding devices applied thereto; and C, an implement which is adapted to perform the tightening operation and to clip the metal tape after it has been secured.

The improved packaging device is adapted 35 not only to the purpose of binding ordinary boxes, crates and packages, but is well adapted to the purpose of tying or securing bundles. For example, the improved device may be employed for securing in bundles, or bales, strips of wood or the like. One useful purpose is that of securing in bundles the arms, legs, rounds, or other members of articles of furniture, for example. In the drawing, A may be regarded

as designating any package or bundle which 55 is to be found or baled.

The improved device B comprises a metal band or tape 1 and a clip 2. The clip 2 preferably is formed of sheet metal. It is in the form of a flat plate or disc, preferably 60 square. In the form shown, it has punched therethrough rectangular slots 2^a and 2^b, separated by a loop 2^c, which is provided by punching the intervening metal upwardly. One end of the metal band 1 is passed 65 through the slot 2^a from above and bent under itself and under the clip, as indicated at 1^a. The other end of the band, after encircling the package or bundle is passed through the loop 2^c, so that the extremity 1^b 70 may be gripped by the tightening implement C.

The tightening implement C is fully disclosed in my copending application No. 668, 75 652, filed in the United States Patent Office on the 15th day of October, 1923. Briefly described, it comprises a foot C', a main lever C² and a movable shear member C³ connected with a rack or plunger C⁴ slidably mounted on the lever C², said rack being 80 actuated by a small lever C⁵ pivoted on the main lever C².

The foot C' is provided with claws or furcations 3, separated by a space 3^a. The foot C' is further provided with a tape-channel 85 4, which is open laterally to admit the tape, as indicated at 4^a. The main lever C² is fulcrumed on a pivot 5, which extends across a recess 6 with which the member C' is provided. The lower end of the lever C² is 90 received in the recess 6, and the recess 6 communicates with the tape slot 4; or, the bottom of the slot 4 may be regarded as the bottom of the recess 6. The lower end of the lever C² has an extension 7 which serves 95 to grip the tape against the bottom of the tape-channel 4 when stretching force is exerted on the lever C².

The member C' is provided with a shear member 8 which co-operates with the movable 100 shear C³. The shear member C³ is capable of limited vertical movement with respect to the member C'. The shear member C³ is provided with slots 9 through which extends screws 10 which serve to secure the shear 105 member to the foot.

In the use of the improved device, a suitable length of metal tape is severed from a

roll; one end of the tape is secured to the clip in the manner illustrated in Fig. 3; the tape is then passed about the package or bundle and the free end inserted through the loop 2^c, as indicated in Fig. 4; the free end portion of the tape is then passed through the stretching implement, which is positioned preferably as shown in Fig. 1, the points of the furcations 3 bearing against the edge of the clip. As the lever C² is actuated, it causes the tape to be gripped by the gripping member 7 against the bottom wall of the tape-channel, and the whole implement then acts as a lever to tighten the tape. After the tape has been drawn sufficiently taut, the loop 2^c is struck with a hammer, thus forcing the loop into the plane of or substantially into the plane of the body of the clip and at the same time deforming the tape and binding it in the slots 2^a and 2^b and about the loop or bridge piece 2^c. The small lever C³ may then be operated to clip off such portion of the tape as extends beyond the shear member. The slots 2^a and 2^b are preferably very narrow so that when the bridge piece is hammered down so as to lie very close to the plane of the body of the clip, the tape will be securely gripped between the edges of the bridge piece and the walls of the slots. As an additional security, the free end 1^b of the tape may be folded back upon the tape as indicated in Fig. 6. By means of the improved packaging device and method, packaging operations of the character indicated may be performed very rapidly and with great security.

What I regard as new, and desire to secure by Letters Patent, is:

1. A packaging device comprising a clip and a metal tape having one end secured to said clip, said clip being formed with a loop adapted to permit the free end of the tape to be passed therethrough, said loop being deformable to enable it to grip the tape. 40

2. A packaging device comprising a clip provided with a pair of slots and with an intervening loop, a metal tape having one end secured to said clip at one of said slots and having the other extremity passed through said loop, said loop being depressed and the tape being deformed and gripped within said slots by the loop. 45 50

3. A packaging device comprising a sheet metal clip provided with a pair of slots and an intervening bridge piece, and a metal tape having one extremity passing through one of said slots from above and bent backwardly under the clip and having the other extremity extending under the bridge piece and gripped thereby within said slots, said last named extremity being bent upon itself over the clip. 55 60

4. The method of packaging which comprises applying to the package a device comprising a metal clip provided with a loop and a metal tape having one end secured to said clip and the other extremity extending through said loop, drawing the tape taut through said loop, and deforming the loop to grip the tape. 65

CHARLES R. HULTGREN.
